UNITED STATES PATENT OFFICE.

WELCOME D. GATCHEL, OF CINCINNATI, OHIO.

DESIGN FOR PHOTOGRAPHIC CHAIR.

Specification forming part of Design No. 7,790, dated October 6, 1874; application filed June 20, 1874.
[Term of Patent 7 years.]

To all whom it may concern:

Be it known that I, WELCOME D. GATCHEL, of the city of Cincinnati, county of Hamilton and State of Ohio, have invented a new and Improved Design for Photographic Chair; and I do hereby declare that the following is a full, clear, and exact description of the same, reference being had to the accompanying drawing forming a part of this specification, in which the drawing is a perspective view.

My design for a photographic chair is fully represented in the accompanying illustrations, to which reference is made.

The design consists of a photographic chair

with one arm and a short back, coming but little below the arm. It is intended for sitters whose pictures are being taken, and has a light, graceful, and singular appearance, which will be readily observed.

Having thus described my invention, what I claim is—

As a new design for photographic chairs, the short back and single arm, arranged with respect to seat as shown and described.

WELCOME D. GATCHEL.
